(57) **CLAIM**

The ornamental design for a footgauge, as shown and described.

DESCRIPTION

FIG. 1 is a top, front, and left side perspective view of a footgauge in accordance with the new design;

FIG. 2 is a top, rear, and left side perspective view thereof;

FIG. 3 is a top plan view thereof;

FIG. 4 is a left side elevational view thereof; the right side elevational view being a mirror image thereof;

FIG. 5 is a front elevational view thereof;

FIG. 6 is a rear elevational view thereof; and,

FIG. 7 is a bottom plan view thereof.

The broken lines shown in FIG. 7 are for the purpose of illustrating portions of the footgauge and form no part of the claimed design.
